UNITED STATES PATENT OFFICE.

GEORGE F. BURTON, OF MENOMONEE, WISCONSIN, ASSIGNOR OF TWO-THIRDS OF HIS RIGHT TO ROCKWELL J. FLINT AND F. J. MCLEAN, OF SAME PLACE.

WAGON-LOCK.

SPECIFICATION forming part of Letters Patent No. 224,070, dated February 3, 1880.

Application filed March 22, 1879.

To all whom it may concern:

Be it known that I, GEORGE F. BURTON, of Menomonee, in the county of Dunn and State of Wisconsin, have invented a new and useful Improvement in Wagons and Locks; and I do hereby declare that the following is a full, clear, and exact description of the same, reference being had to the accompanying drawings, forming part of this specification, in which—

Figure 1 is a top view of a portion of a wagon with my improved lock applied to it, also showing the improved reach-connection. Fig. 2 is a longitudinal vertical section of the same. Fig. 3 is a side elevation. Fig. 4 is a vertical cross-section in the line $x x$ of Fig. 2. Fig. 5 is a detail view of the circle-plate or fifth-wheel. Fig. 6 is a section across one of the guides, clips, and trips of the locking devices. Fig. 7 is a similar section, showing an ordinary clip-iron in place of the one shown in Fig. 6. Fig. 8 is a detail section of one of the locking devices, axle, and fifth-wheel. Figs. 9 and 10 are sections of the gripping device, trip, and fifth-wheel, illustrating the operation of the gripping device. Fig. 11 is a section similar to Fig. 8, but showing the gripping device applied in rear of the axle of the wagon.

The nature of my invention consists in certain constructions, combinations, and arrangements of parts, as hereinafter described and specifically claimed, whereby the gripping devices shown in Letters Patent granted to me on the 5th day of November, 1878, can be made, respectively, of a single piece of metal; the springs for keeping the locking devices in condition ready for action can be housed and guarded from undue strain, and their housings made to answer for limiting the movement of the gripping plates while they are being freed from their gripe upon the fifth-wheel; the trips can be made adjustable separately on the hounds or braces, and the rear part of the reach, where it is connected with the short bar extending back from the front axle, can be provided with a firmer rolling bearing.

A in the accompanying drawings represents the front axle of a wagon; B, the cross-bar or bolster; C, the king-bolt; D, the fifth-wheel; E, the front part of the reach; F, the

rear part of the reach, and G the portion to which the tongue is attached, and which has a vibration sidewise about equal to the movement of the gripping-plates I I, in order to release the plates. The connections H, by which the rear part of the reach F is fastened to the front part, E, consist, in part, of semicircular castings $a a$, of oblong form, and across these castings slots a' are made, as shown. The under sides of the castings are arched, in order to make the castings light, and also afford room for the heads of the fastening-bolts b , which pass up loosely through the slots. Two other oblong castings, b' , made with nearly semicircular recesses on their under sides, are fitted upon the castings $a a$, and kept from longitudinal movement by end shoulders, b^2 , formed on castings b' , as shown in Fig. 2. The two sets of castings $a a b' b'$ are fastened to their respective places by screws $b^3 b^3$, and they are coupled together by the bolts $b b$, with nuts on their upper ends, as shown.

This construction of the connections H gives a firm longitudinal bearing for the rear part of the reach upon the front part, E, which is rigid with the fifth-wheel, and at the same time either the front or hind wheels, and the respective axles with them, can roll freely in a vertical plane at right angles to the reach, the long broad bearings $a b'$ permitting this movement, while they prevent all longitudinal movement between the parts E and F by means of the shoulders b^2 .

The fifth-wheel D is made with an opening, c , between its ends, in order that the gripping-plates I may be placed upon it. The gripping-plates have slots i through them of a size corresponding very nearly with the thickness of the fifth-wheel, and these slots for about one-half their length are parallel with the top and bottom of the fifth-wheel, and for the remainder of their length they diverge on oblique lines, as shown at $i' i^2$. By this construction a firm frictional gripe of the plates is secured upon the top and bottom of the fifth-wheel when the front wheels of the axle become chocked by any obstacle in front of them.

The action of the plates while gripping will be understood by examining Fig. 9 of the drawings, and their action while the wagon is

moving forward will be understood from Fig. 10 of the drawings. In Fig. 9 the strain comes diagonally against the parallel portions of the slots, and in Fig. 10 the plate is thrown in a reverse direction, and the flaring portions of the slots permit the plates to free themselves from the fifth-wheel. There is, as usual, one gripping-plate, I, on each side of the tongue, in order that the wagon shall be locked on either side, whether the right or left hand wheel of the wagon is suddenly arrested in its revolution by an obstruction.

The springs J, which keep the gripping-plates in their proper gripping position, are coiled around the brace-rods K and inclosed or housed by a tube, d, which is attached to a bracket of the axle A, as shown. The tube d is open at its front end and perforated, so as to permit the rod K, after it is passed through the plate I, to pass through it. The forward ends of the springs extend beyond the front ends of the tubes and bear against the gripping-plates, and thus there is room enough between the plates I and the tubes to permit the plates to move back from the position shown in Fig. 9 to that shown in Fig. 10. When the plates are thus moved back the tubes act as checks or stops to prevent strain on the connections. A stop or nut, e, on the end of the respective rods K limits the forward movement of the rods.

The trips or releasing devices L are applied to the top of the rods K, and are made separate from the rods, being held in position by means of ordinary adjustable clips l. The rear ends of the trips rest upon the top of the fifth-wheel, and are bent so as to extend under it. By sliding the trips slightly backward the wear between them and the plates I will be com-

pensated for. These clips act the same as usual, tripping or releasing the gripping-plates when it is proper for them to be inactive.

In Fig. 11 the locking device is represented as applied in rear of the axle; but the operation under this arrangement is substantially the same as when applied at the front of the axle. In this illustration the brace and trip are applied to a screw-bolt, m, with a stop-nut, n, and the spring is applied upon a rod, K', which supports the spring J and tube d.

What I claim as new is—

1. In a wagon or vehicle, the combination of a swinging axle-tree, a rigid fifth-wheel, and a frictional gripping device, made in one piece and provided with gripping portions, as described, and connected to the axle-tree, and locking itself upon the fifth-wheel when the axle has a tendency to swing independently of the tongue of the wagon, substantially as and for the purpose described.

2. The combination of the spiral spring J, rod K, stop-tube d, and plate I, substantially as and for the purpose described.

3. The trips L, in combination with the adjustable clips l, rods K, and plates I, substantially as and for the purpose described.

4. The combination of the front and rear parts, E F, of the reach, fifth-wheel D, and elongated semicircular slotted bearings H, having end stops, b², substantially as and for the purpose described.

Witness my hand in matter of my application for a patent for improvement in wagon-locks.

GEORGE F. BURTON.
